ADJUSTABLE CLOTHESLINE SUPPORT

Alexander O. Johnston, Pittsburgh, Pa.

Application June 21, 1935, Serial No. 27,699

2 Claims. (Cl. 248—327)

This invention relates to supports for clothes-lines and more particularly to adjustable hangers for supporting clothes-lines in the basements of homes and like places.

The main object of this invention is to provide means of simple, efficient and durable nature for supporting clothes-lines in the basements of homes whereby such lines may be readily strung or erected and drawn or stretched to the desired degree of tautness.

Another object is to provide means for adjustably mounting clothes-line hangers in the basements of homes and the like where additional head room is often required whereby such hangers and the line supported thereon may be readily and easily raised and moved to out of the way position when not in use without disconnecting such line from the hangers.

A further object is to provide a hanger having means associated therewith for drawing taut or stretching the line supported thereon in such a manner as to eliminate the exertion and difficulty encountered in the usual method employed to accomplish this purpose.

A further object is to provide a set of clothes-line hangers one of which forms an anchor for one end of the line and another an anchor for the other end of the line and having means associated therewith for drawing the line taut and releasably holding it in its stretched condition.

A still further object resides in an anchoring means for one end of a clothes-line whereby the line may be readily stretched or drawn taut to remove sagging in the line either before or after the clothes have been hung thereon.

These and other objects which will be herein-after made apparent to those skilled in this particular art are accomplished by means of this invention, one embodiment of which is described in the following specification and illustrated in the accompanying drawings wherein:

Figure 1 is a plan view of a clothes-line supported on hangers of my improved construction and illustrates one arrangement of such hangers, portions of the line and the frame to which the hangers are attached are broken away for convenience of illustration;

Fig. 2 is a view in side elevation of one of the intermediate hangers used in supporting the clothes-line;

Fig. 3 is a plan view of the hanger shown in Fig. 2 with its supporting bar shown in section;

Fig. 4 is a view in side elevation of the hanger forming the anchor for one end of the clothes-line;

Fig. 5 is a front elevation of the hanger illustrated in Fig. 4;

Fig. 6 is a side elevation of the hanger for anchoring the other end of the clothes-line and for stretching or tightening the line and also illustrates the bracket for supporting the hangers from the ceiling beams or floor joists found in the basement of a home of the usual construction;

Fig. 7 is a plan view of the hanger shown in Fig. 6 with the supporting bar shown in section;

Fig. 8 is a front elevation of the brackets for supporting the hangers;

Fig. 9 is a top plan of the bracket shown in Fig. 8;

Fig. 10 is a section taken on line X—X of Fig. 8;

Fig. 11 is a side elevation of a modified type of hanger and another form of supporting bracket; and

Fig. 12 is an enlarged view partially in section illustrating the detail construction of the hanger shown in Fig. 11.

Referring to the drawings in detail A represents a wire or rope line suitable for use in the drying of laundered articles, having one end thereof anchored to a hanger or support B and extending around one or more intermediate anti-friction hangers C that are spaced from the hanger B, and from each other, with its opposite end attached or anchored to a hanger D which is provided with a suitable mechanism for tightening or stretching the line as will hereinafter be more fully explained.

Each of the hangers B, C and D is secured to the web of a channel bar 2 that are supported for vertical movement in brackets 3 which are attached to the ceiling beams or floor joist E usually found in the basements of homes. While the beams or joist E present a most convenient form of support for the brackets 3 it is obvious that other supports located elsewhere than in a basement may be employed for supporting the hangers B, C and D without departing from my invention.

Each of the brackets 3 comprises a back wall 4 which is adapted to abut against and to be secured to the face of the beam or joist E and a bottom wall 5 at right angles to the wall 4 which is adapted to be secured to the under edge of the beam or joist E. The outer face of each bracket 3 is provided, at its top and bottom, with outstanding lugs 6 and 7 which are apertured to form an opening for receiving the

channel bar 2. The channel bar 2 is yieldably held in place in its respective bracket 3 by a bowed spring 8 which has its ends attached to the lugs 6 and 7 and is bowed so that the central portion projects toward the wall 4 and bears against the web of the bar 2 whereby the bar is pressed and frictionally held against the wall 4. Thus it is apparent that when the line is not in use each of the channel bars 2 together with its respective hangers B, C or D may be individually pushed upwardly through the bracket 3 until the lower ends of the bars and the line supported on the hangers carried thereby are substantially flush with the bottoms of the beams or joist E and, as a result, the line and its supporting hangers are moved into an out of the way position.

The hanger B to which one end of the line A is anchored or secured when it is desired to string 20 or erect the line comprises a hook 10 which is riveted to the web of one of the channel bars 2.

Each of the anti-friction hangers C, which supports the line A intermediate of its ends, is of similar construction and each includes a horizontally positioned groove wheel or sheave 11 that is journaled on an upstanding pin 12 formed on a bracket 13 that is secured to the web of another of the channel bars 2.

The hanger D comprises a grooved wheel or 30 pulley 14 having an upstanding pin 15 on the grooved surface thereof to which the opposite end of the line A is adapted to be secured. This wheel or sheave 14 is secured to a shaft 16 that is journaled in the arms of a clevis 17. The clevis 35 17 is pivoted at its base to an angle bracket 18 which is secured to the end of another of the channel bars 2.

In order that the line A extending around the wheels 11 and anchored to the hook 10 and the 40 pin 15 may be readily tightened or stretched to support the load imposed thereon, a handle 20 is secured to one end of the shaft 16 so that the wheel or sheave 14 may be readily and easily turned to shorten the line between the hangers B 45 and D, and in order that the line will remain taut after it has been stretched the wheel 14 is also provided with ratchet teeth 21 which are engaged by a dog 22 pivoted to the clevis 17. The dog 22 is adapted to slide over the teeth 21 when the wheel 50 14 is turned to stretch the line A, and to engage the teeth and prevent the wheel from turning in the opposite direction.

To prevent the clevis 17 from swinging about its pivot on the bracket 18 and at the same time 55 to permit the clevis to be readily adjusted to move the wheel 14 to any desired position relative to the bracket, the outer end of the bracket is provided with a series of spaced notches 23 and a slotted pin 24 is slidably mounted in the base of a 60 the clevis 17 which is adapted to be moved into one of the notches 23 when the wheel or sheave is in its proper position to lock the clevis in its set position and prevent any turning movement thereof relative to the bracket 18.

65 In Figs. 11 and 12 I have illustrated a modified form of supporting bracket which may be used with any of the hangers B, C, and D. In this modification the hangers are secured to a substantially T-shaped bracket 25, the cross bar of 70 which is adapted to be secured to a suitable wall or other supporting member 26. In this exemplification of my invention I have also shown a modified form of a locking device for preventing the clevis 17 from turning relative to its supporting bracket 25. In this modification the base of

the clevis 17 is provided with rearwardly projecting spaced apertured lugs 27 through which extends a pin 28 that secures the clevis to the bracket 25. A pin 29 is mounted in the base of the clevis 17 between the lugs 27 and is normally and yieldingly in engagement with one of a series of notches 33 formed in the outer end of the bracket 25 by a spring 32 that is mounted in a slot 31 in the pin 29 and has one end secured to a pin 30 which extends through the slot 31 and anchors the pin 29 in the clevis 17. The pin 29 yieldingly prevents the clevis from turning relative to the bracket 25.

Bracket 25 provides a means for supporting the tightening mechanism in such other places as an 15 attic or outdoors where it may be used either in combination with hangers B, C or D, or in combination with the ordinary means of supporting the line at the end and intermediate points and where it might be desirable to remove the tightening mechanism when not in use, leaving the bracket 25 as a permanent fixture.

From the foregoing description it is apparent that I have produced a series of hangers for supporting a clothes-line which may be readily adjusted to the desired height and easily stretched or drawn to the desired tautness and when the line is not in use the hangers may be readily moved to an out of the way position after the tension in the line has been released. This is 30 accomplished by raising the dog 22 and allowing the wheel 14 to turn. Further, from the construction of the brackets 3 it is apparent that although the bars 2 may be readily moved up and down within the brackets, the lugs 6 and 7 are so spaced apart that rotative movement of the bars, due to the tightening of the line A, is prevented.

While I have described one embodiment of my 40 invention and illustrated the hangers in connection with the ceiling beams or floor joist it is to be understood that my invention may be embodied in other forms and used in connection with other supporting means without departing from the spirit of my invention or the scope of 45 the appended claims. For example, other means besides those illustrated in Figs. 7 and 12 may be employed for positioning the clevis 17 on the bracket 18, such as forming the clevis 17 with a rearwardly projecting lug, which when the clevis 50 is positioned on the bracket 18, would enter one of the notches on the bracket and preventing the clevis turning relative to the bracket. Or the outer end of the bracket may be made of octagon or hexagon shape and a flat surface on the clevis 55 17. In such construction the flat surface on the clevis would cooperate with one of the octagon or hexagon shaped surfaces when the clevis was on the bracket and prevent relative turning therebetween.

60 What I claim as new and desire to secure by Letters Patent is:

1. Apparatus for supporting a clothes line at different elevations, comprising a substantially L-shaped bracket adapted to be secured to the bottom and side of a floor joist or the like and having unitarily formed spaced apertured lugs projecting outwardly from one side thereof with the apertures therein aligned, a line supporting member of channel shape vertically slidable 70 through the apertures in said lugs and having a line tensioning device secured to its lower end and an arcuate spring having its ends attached to the lugs in the apertures thereof with the intermediate portion thereof projecting inwardly toward 75

said bracket into yieldable engagement with the web of said channel member to press the same into frictional contact with said bracket whereby said member is yieldably held at different elevations within said bracket.

- 5 2. Apparatus for supporting a clothes-line at different elevations comprising a substantially L-shaped bracket adapted to be secured to the bottom and side of a floor joist or the like and 10 having unitarily formed and vertically spaced apertured lugs projecting outwardly from the front face thereof with the apertures therein aligned, a line supporting member of channel

shape slidably extending through the aligned apertures in said lugs and having a right angle extension on its lower end adapted to receive a line tensioning device, and a vertically extending bowed spring having its ends attached in the 5 apertures of said lugs with the intermediate bowed portion projecting toward the front of said bracket into engagement with said line supporting member for yieldably pressing the same into frictional contact with said bracket whereby the 10 member is yieldably held at the desired elevation within said bracket.

ALEXANDER O. JOHNSTON.
